UNITED STATES PATENT OFFICE.

ALGERNON S. HUBBELL, OF NORWICH, CONNECTICUT.

PEN-HOLDER.

SPECIFICATION forming part of Letters Patent No. 403,190, dated May 14, 1889.

Application filed August 8, 1888. Serial No. 282,277. (No model.)

To all whom it may concern:

Be it known that I, ALGERNON S. HUBBELL, a citizen of the United States, residing at Norwich, in the county of New London and State 5 of Connecticut, have invented certain new and useful Improvements in Pen-Holders, which improvements are fully set forth and described in the following specification, reference being had to the accompanying sheet of 10 drawings.

This invention relates to that class of pen-holders in which the pen and its connected tubular support may be drawn partially or wholly within the handle of the holder for the 15 purpose of concealing and protecting the pen-point when not in use.

My immediate object is to so simplify the construction of such pen-holders that they may be cheaply produced and easily operated. 20 To this end I have improved particularly the form and mode of construction of the sliding pen-support, as hereinafter described in detail, and specified in the claim.

The annexed drawings illustrate said invention, Figure 1 being a side view of a complete pen-holder of my improved construction, showing the pen and its tubular support drawn out as in the act of writing. Fig. 2 is an enlarged longitudinal section of the slotted end 30 of such a holder with the pen drawn within the handle. Fig. 3 is a plan of the blank from which the sliding pen-support is formed, showing both the punched blank and the same after lip d' has been bent forward over the body portion. Fig. 4 shows said pen-support bent to shape and ready to be attached to the slotted handle-section.

Referring to the drawings, the letter a indicates a handle of wood, ivory, celluloid, or 40 other suitable material, having its pen-engaging end slotted, as at b , to receive the section that supports the pen c . Said pen-support is made of sheet metal, (or of similar material that may be readily punched and bent to 45 shape,) and is formed with a body portion substantially rectangular, (see d ,) and an end projection or lip, d' .

In shaping up my pen-support from said blank the end lip, d' , is first bent forward un-

til it lies on or very close to the body portion 50 d , the extreme end of said lip being preferably bent slightly outward, as illustrated in Fig. 2. The office of the lip d' thus bent is threefold: First, it serves as a spring-clamp to retain the pen within the tubular support, 55 the body of the pen being forced over said lip as said pen is inserted in the tube; second, the free end of lip d' , when drawn forward, abuts a lug, a' , at the open end of slot b , and thus serves as a positive stop to prevent the 60 tube from being drawn completely off from the handle-section, and, third, the free end of said lip d' rests at all times against the lower wall of slot b and serves as a friction-brake to prevent the pen from sliding too freely into 65 the handle-section. Without some such provision the downward pressure of the hand during the act of writing would force the handle downward through the tubular pen-support. 70

The lug a' , above referred to, is preferably integral with the handle a , and is provided by leaving said lug projecting when the slot b is cut.

The barrel of the pen-support is formed by 75 swaging or rolling in the longitudinal edges of the body-section d . The tubular pen-support thus provided is attached to the handle a by simply sliding said tube over the lower limb 80 of the slotted end of said handle. As the free end of the spring-lip d' passes lug a' said lip snaps downward behind said lug and the pen-holder is ready for the pen.

Having thus described my invention, I 85 claim—

In combination with a longitudinally-slotted holder, a pen-support formed with a barrel portion movably located on one limb of said holder and provided with an inturned spring-lip that bears frictionally against the other of 90 said limbs, as set forth, said holder being formed with a stop-lug, a' , at its open end adapted to engage and check the pen-support, substantially as and for the object specified.

ALGERNON S. HUBBELL.
